UNITED STATES PATENT OFFICE.

BERTON L. WRIGHT, OF BRIDGEPORT, CONNECTICUT, ASSIGNOR OF TWO-THIRDS TO SAMUEL A. BURNS, OF SAME PLACE.

CAR-BRAKE.

SPECIFICATION forming part of Letters Patent No. 400,029, dated March 19, 1889.

Application filed December 26, 1888. Serial No. 294,621. (No model.)

To all whom it may concern:

Be it known that I, BERTON L. WRIGHT, a citizen of the United States, residing at Bridgeport, in the county of Fairfield and State of Connecticut, have invented certain new and useful Improvements in Car-Brakes; and I do hereby declare the following to be a full, clear, and exact description of the invention, such as will enable others skilled in the art to which it appertains to make and use the same.

My invention is especially adapted for use upon street-railway cars, and has for its object to produce mechanism which shall be simple, compact, durable, and inexpensive, and which will enable the driver, when the brake is locked, to release it by a slight backward movement of the handle and without any forward movement whatever, no manipulation of the foot-dog or rotary movement of the handle being necessary in the act of unlocking the brake. With these ends in view I have devised the novel mechanism, of which the following description, in connection with the accompanying drawings, is a specification, numbers being used to denote the several parts.

Figure 1 is a partial elevation of a street-railway car, illustrating the application of my novel mechanism, the brake being supposed to be in the locked position, as the chain is shown as wound upon the cone; Fig. 2, a section of my novel mechanism, certain of the parts being in elevation, showing the position of the parts during the operation of locking the brake, the foot-dog being disengaged from the ratchet; Fig. 3, a similar section showing the position of the parts in the unlocked position; Fig. 4, an inverted plan view of the winding-sleeve detached; Fig. 5, an inverted plan view of the ratchet detached; Fig. 6, a plan view of the cone or winding-drum detached; Fig. 7, a partial side elevation of a car-platform, illustrating a form in which the winding-sleeve is placed below the platform, and slight changes are made in the details of construction, the chain being wound upon the cone, as in Fig. 1, and the foot-dog in engagement with the ratchet; Fig. 8, a central section, partially in elevation, corresponding with Fig. 7, the position of the parts corresponding with Fig.

2—that is, illustrating the operation of locking the brake—the foot-dog being disengaged; Fig. 9, a similar section, the parts being in the unlocked position, as in Fig. 3; Fig. 10, a plan view of the cone or winding-drum in Figs. 8 and 9 detached; Fig. 11, an inverted plan view of the winding-sleeve detached; Fig. 12, a vertical section of the winding-sleeve; and Fig. 13, a section of the brake-spindle on the line *xx* in Fig. 8, looking down.

1 denotes the brake-staff; 2, the handle; 3, the car-platform, and 4 the guard-rail through which the brake-staff is ordinarily passed or by which it is supported, these parts being of the ordinary or any preferred construction.

5 denotes a base-plate rigidly secured to the front of the platform and having an opening in which the winding-drum or cone 6 is journaled. The brake-staff passes down through the winding-drum, and is provided at its lower end with the usual elastic ball, 7, for the protection of a horse should it fall and the car pass over it. The brake-staff turns freely in the winding-drum, and the latter turns freely in the base-plate. At the upper end of the winding-drum is a flange, 8, which rests upon the base-plate, and is provided in its upper side with openings 9, the purpose of which will presently be explained.

28 denotes the locking-chain, one end of which is attached in any suitable manner to the winding-drum, the other end (not shown) being attached to the brake-lever or other suitable operating mechanism, which, however, has nothing to do with my present invention.

10 denotes the ratchet, which is provided in its under side with a recess, 11, which just receives the flange of the winding-drum, leaving the latter free to turn within said recess.

12 denotes the usual foot-dog, which is adapted to engage the ratchet in the ordinary manner. Above the ratchet is a housing, 13, held in position by a collar, 14, rigidly attached to the brake-staff in any suitable manner—for example, by a set-screw, as shown in the drawings. Within the housing is a winding-sleeve, 15, through which the brake-staff passes freely. In the under side of the winding-sleeve I form a recess, 21, the bottom

of said recess consisting of inclines 16, terminating abruptly in shoulders 17.

18 denotes lugs or pins projecting from the under side of the winding-sleeve and adapted 5 to pass through openings 19 in the ratchet and to engage openings 9 in the winding-drum.

It will be noticed in Fig. 3 that in the raised position of the winding-sleeve—that is, the unlocked position of the brake—lugs 18 remain in engagement with the ratchet, but are wholly disengaged from the winding-drum. It will be seen, furthermore, from Figs. 4, 5, and 6, that lugs 18 and openings 19 in the ratchet in which said lugs engage are at 15 equal distances apart, said lugs and openings being so located that the lugs will register with openings 9 in the winding-drum at a certain position, but in that position only.

20 denotes a collar on the brake-staff, which 20 is adapted to engage recess 21 in the bottom of the winding-sleeve, said collar being provided on its upper side with cams 26 and shoulders corresponding with the inclines and shoulders in said recess. This collar is rigidly secured to the brake-staff in any suitable 25 manner, preferably by drop-forging thereon.

22 is a spring within the housing, the upper end of which bears against the under side of the top of the housing and the lower end 30 against the top of the winding-sleeve, its action being to keep lugs 18 in engagement with the openings of the ratchet and to force them into engagement with openings 9 in the winding-drum as soon as said lugs and openings 35 are caused to register by forward movement of the brake-staff.

It will be seen that my improved construction is such as to thoroughly protect all portions of the mechanism from mud, snow, and 40 ice, and, furthermore, that the action of spring 22 is to lift the housing away from the ratchet, so that there will be no friction, the housing, however, being placed close to the ratchet and locked there by adjustment of collar 14.

45 In all car-brakes, so far as I am aware, that have gone into use the driver has been required, in order to release the brake, to give the handle a violent turn forward in order to release the foot-dog and then to kick the latter out of engagement with the ratchet, letting go of the handle at the same time, which flies violently around. There is necessarily, therefore, considerable loss of time in releasing the action of the brake. This has been 55 found a serious trouble in starting with heavy loads and also in using horses which are inclined to pull irregularly, it being desirable that when the horse or horses start forward suddenly it be within the power of the driver 60 to instantly relieve all pressure of the brake upon the wheels.

55 My invention operates as follows: The brake is set or locked in the usual manner—that is, by turning the handle forward and placing the foot-dog in engagement with the ratchet to lock it, it being immaterial whether the foot-dog is held in contact with the ratchet

during the operation of locking or setting the brake or not. During the operation of locking the brake the position of the parts is as 70 in Fig. 2. Shoulders 17 in the recess in the bottom of the winding-sleeve are engaged by the corresponding shoulders upon collar 20, so that as the brake-staff is turned forward the winding-sleeve is necessarily carried by 75 the engagement of said shoulders, and the ratchet and winding-sleeve are carried through the engagement of lugs 18 with openings 19 and 9. The operation of locking or setting the brake is thus seen to be precisely 80 the same as in the ordinary brakes in use. The unlocking operation, however, is entirely different. No manipulation of the foot-dog is necessary, and no rotary movement of the handle and staff. The handle is simply given 85

a quick movement backward in use one-eighth of a turn, more or less. The effect of this movement is to cause inclines 16 in the winding-sleeve, the latter being held against rotation by the engagement of lugs 18 with the 90 openings in the ratchet to ride up the cams upon collar 20, thus raising the winding-sleeve and releasing the lugs from engagement with openings 9 in the winding-sleeve. The latter, being now entirely free, is turned back 95 violently by the tension of the locking-chain. As the special construction and arrangement of the brake-lever and the manner in which the brake-shoes engage the car-wheels have nothing whatever to do with my present 100 invention, I have not deemed it necessary to illustrate them in the drawings, but simply to show the chain, the opposite end of which is of course connected to the brake-lever or other operative mechanism, and the manner in which 105 it is wound upon the drum. When it is desired to set or lock the brake again, the handle is turned forward, as before. Spring 22, as already stated, acts to retain lugs 18 in engagement with openings 19 in the ratchet, 110 and just as soon as these openings are brought to register with openings 9 in the winding-drum said spring will force the lugs into engagement therewith, so that the chain will be wound upon the drum and the brake set, 115 as before. In the forms illustrated in Figs. 7 to 13, inclusive, the housing, winding-sleeve, and spring are placed under the car-platform. The inclines and shoulders are formed in the bottom of the winding-sleeve, 120 the same as before, and lugs upon the bottom of the winding-sleeve engage openings in the top of the winding-drum, the same as before. The ratchet, of course, lies above the platform, and in this form is provided with a sleeve, 23, 125 which extends down through the winding-sleeve, and is provided with a lug or pin, 24, which engages a vertical groove, 25, within the winding-sleeve. In this form collar 20 is provided with cams 26, projecting from the 130 sides thereof, which engage the inclines within the winding-sleeve.

27 denotes braces in which the lower end of the brake-staff is journaled and upon which

the winding-drum rests. These braces are rigidly secured to the under side of the platform and support the lower end of the brake-staff in use.

5 It will be obvious that the details of construction illustrated in the drawings may be greatly varied without departing from the principle of my invention.

I claim—

10 1. The combination, with a brake-staff having cams, and a winding-drum to which the chain is connected, of a winding-sleeve on said staff, which is adapted to engage the drum and is engaged by the cams, so that when the staff is turned forward the sleeve and drum are carried thereby, and when the staff is turned backward the sleeve is raised and disengaged from the drum.

20 2. In a car-brake, a staff having cams, a winding-drum loose on said staff, and a winding-sleeve having lugs to engage the winding-drum, and inclines and shoulders engaged by said cams and adapted to engage the drum, whereby when the staff is turned forward the 25 winding-sleeve and cone are turned to set the brake, and when the staff is turned backward the winding-sleeve is raised to release the cone, substantially as described.

30 3. In combination, a brake-staff having cams, a winding-drum loose upon the staff to which the chain is connected and which is provided with openings in its upper side, and a winding-sleeve having inclines and shoulders engaged by the cams, and lugs adapted 35 to engage the openings in the drum, whereby when the staff is turned forward the winding sleeve and drum are carried thereby, and when turned backward the winding-sleeve is raised, as and for the purpose set forth.

40 4. In combination, a brake-staff having cams, substantially as shown, a winding-drum loose upon the staff to which the chain is connected, and which is provided with openings in its upper side, a ratchet having openings 45 adapted to register therewith in one position only, a winding-sleeve having inclines and shoulders adapted to be engaged by the cams, and lugs engaging the openings in the ratchet, and adapted to engage the openings in the

drum, whereby when the staff is turned forward the winding-sleeve, ratchet, and drum are carried thereby, and when the staff is turned backward the winding-sleeve is raised and the lugs are disengaged from the drum, leaving the latter free to be turned backward by the tension of the chain.

5 5. In combination, a brake-staff having cams, substantially as shown, a winding-drum loose upon the staff to which the chain is connected and which is provided with openings in its upper side, a ratchet having openings adapted to register therewith in one position only, a winding-sleeve having inclines and shoulders adapted to be engaged by the cams, lugs engaging the openings in the ratchet and adapted to engage the openings in the drum, and a spring acting to hold said lugs in engagement with said openings, as and for the purpose set forth.

6. The combination, with a brake-staff having cams, a winding-drum loose on said staff and having openings 9, and a ratchet having openings 19, of a housing, substantially as shown, a winding-sleeve within said housing having inclines and shoulders adapted 75 to be engaged by said cams, lugs engaging openings 19 and 9, and a spring bearing against the upper end of the housing and the winding-sleeve, as and for the purpose set forth.

7. A base-plate, a winding-drum journaled therein and having a flange resting thereon and provided with openings in its upper side, a ratchet having a recess in its under side to receive said flange, and openings 19, 85 in combination with the brake-staff passing through said drum and ratchet, cams upon said staff, a winding-sleeve having lugs to engage the winding-drum, inclines and shoulders engaged by said cams, and a foot-dog 90 adapted to engage the ratchet.

In testimony whereof I affix my signature in presence of two witnesses.
